Patented July 25, 1922.

UNITED STATES PATENT OFFICE.

FREDERICK B. SEARLE, OF DENVER, COLORADO.

STEAM DRIFTER MECHANISM FOR LOCOMOTIVES.

1,423,688.

Specification of Letters Patent. Patented July 25, 1922.

Application filed June 11, 1920. Serial No. 388,252.

To all whom it may concern:

Be it known that I, FREDERICK B. SEARLE, a citizen of the United States, residing at the city and county of Denver and State of Colorado, have invented certain new and useful Improvements in Steam Drifter Mechanism for Locomotives; and I do declare the following to be a full, clear, and exact description of the invention, such as will enable others skilled in the art to which it appertains to make and use the same, reference being had to the accompanying drawings, and to the characters of reference marked thereon, which form a part of this specification.

The object of this invention is to provide means for supplying moist steam to the superheaters and cylinders of a locomotive when the same is drifting, in order to maintain a fairly even temperature and to insure proper lubrication, said steam being automatically shut off when the engine is stopped. Heretofore, when the throttle has been closed for drifting, all steam has been cut off permitting the temperature to rise rapidly. This has affected lubrication while the sudden temperature changes have affected the joints of the fittings.

Briefly, the invention comprises a conduit adapted to carry steam from the boiler to the header, from where it will be conducted into the superheaters and cylinders when the throttle is closed. This conduit is provided with a valve, operated by air under pressure, and the air is supplied to the operating part of the valve by means of a feeder which is driven from some moving part of the locomotive, such as one of the trailer wheels. In the drawing:

Fig. 1 is a diagrammatic showing of parts of a locomotive, showing the application of the invention.

Fig. 2 is a section through the air feeder; and

Fig. 3 is a section through the steam-controlling valve.

The drawings represent a conventional locomotive having a boiler B, cab C, firebox F, running board R. The boiler is preferably provided within the cab with a turret 10, from which there leads a moist steam conduit 12, which may be equipped with a hand-operated valve 14. The conduit 12 leads to the header 15 of the locomotive, which normally receives live steam through a dry pipe 16, leading from the steam dome

18, the steam being fed from said header 15 by means of superheater pipes 20, which lead to the cylinders 22. The conduit 12 is provided, preferably just forward of the cab, 60 with a valve housing 25, having a partition 26 provided with a relatively deep seat for a valve 28, mounted on a valve stem 30. The valve stem 30 extends into a casing 32, provided with an adjustable leakage screw 33, 65 by means of which leakage of the air from the casing 32 may be controlled. The casing 32 is provided with an extension 34, threaded into an opening in the valve housing 25. In this manner the casing may be removed with 70 the housing 25, and the valve 28 thereby withdrawn for grinding purposes when necessary. The extension 34 is provided with a leakage port 35, for steam, so that any steam which might leak along the stem 75 30 will be prevented from passing into the air casing 32. The stem 30 is operated by means of a piston 36, normally urged toward valve-seating position by means of a spring 38, which bears at one end against the piston 80 36 and at the other end against an adjustable sleeve 40, threaded into the upper end of the casing 32, and also serving as a guide for the valve stem 30.

An air pipe 42 leads into the casing 32 85 from a cylinder 44, mounted upon the running board R, this cylinder being open at both ends and containing a piston and a main portion 45, to which there is connected, by a shaft 46, a spaced auxiliary portion 48, 90 whereby an air-receiving pocket 49 is provided between the said two portions 45 and 48. The piston is driven by means of a connecting rod 50, operated by a crank 52, driven by a groove pulley 54, which receives 95 a belt 55, connected with a pulley 56 on a trailer wheel 58. Air under pressure is fed into the receiving chamber 49 in the cylinder 44, from a small pipe 60, which may have a reduced portion 62 to cut down air pressure, which pipe 60 leads from the main air line 64 of the engine.

In operation, when the locomotive is moving, the trailer wheel 58, through the belt 55, will reciprocate the piston 45 so that the 105 pocket 49 when opposite to the pipe 60, will receive a charge of air under pressure. At the opposite end of the stroke, said charge will be delivered to the pipe 42, the pipe 60 being closed by the auxiliary piston portion 110 48 when in this position. In this manner, small charges of compressed air are fed

continuously through the pipe 42 to the air chamber 32. The leakage screw 33 will be so adjusted that sufficient air pressure will be maintained within the chamber 32 to 5 raise the piston 36 against the tension of spring 38 and thereby open valve 28. This will permit the passage of moist steam from the boiler through the conduit 12 to the header 15, whence it will be carried to the 10 cylinders 22, thereby lubricating the same when the throttle is closed.

When the engine is not running, there will be no reciprocation of the piston 45, so that no air will be fed to the casing 32 and 15 the valve 28 will remain closed. This produces a practically fool-proof device and prevents the possibility of a small amount of steam being fed to the cylinders 22 so that the engine might be caused to move, 20 when not desired.

I claim:

1. In a drifter lubricator for locomotives having a live steam conduit adapted to be connected with the cylinders of a locomotive, a pressure controlled valve in said conduit, and a source of compressed air, means 25 operated by a moving part of said locomotive, when the latter is running, for intermittently transferring air from said com-

pressed air source to said valve, said means comprising a cylinder, a reciprocating piston therein, a crank and connecting rod for reciprocating said piston, an annular pocket in said piston, an intake and an outlet pipe entering said cylinder and so located that 35 the pocket engages alternately with first one and then the other whereby air is intermittently transferred from the intake pipe to the outlet pipe.

2. In combination, a locomotive having a 40 boiler, a cylinder and a part which moves when the locomotive drifts, a moist steam connection leading from the boiler to the cylinder, a valve in said connection, means to operate said valve, said operating means 45 being connected with said moving part and adapted to be moved thereby, said operating means comprising a member connected with the valve, an air conduit to supply air under pressure to said member, an air cylinder, a 50 piston having a pocket positioned in said air cylinder, a connection from a source of compressed air to said cylinder, said air conduit also leading to said cylinder, and means to reciprocate said piston to feed 55 charges of air intermittently to said conduit.

In testimony whereof I affix my signature,
FREDERICK B. SEARLE.
